WORK FEEDING MECHANISM FOR SEWING MACHINES

Arthur N. Hale, Stratford, and Russell Carmichael, Devon, Conn., assignors to The Singer Manufacturing Company, Elizabeth, N. J., a corporation of New Jersey

Application December 23, 1948, Serial No. 66,924

12 Claims. (Cl. 112—98)

1

This invention relates to sewing machines and more particularly to work-feeding mechanisms for ornamental stitching machines of the type disclosed for example in the U. S. patents of F. M. Card, No. 2,216,096, issued Sept. 24, 1940, and C. M. Ambergrombie, No. 1,012,182, issued Dec. 19, 1911.

The primary object of the present invention is to provide an improved quiet running high-speed work-feeding mechanism adapted for feeding the work in opposite directions in a pre-determined sequence.

The foregoing and other objects and advantages, together with means whereby the same may be carried into effect, will best be understood from the following description of a preferred embodiment thereof illustrated in the accompanying drawings, in which:

Fig. 1 is a bottom plan view of the bed of a sewing machine equipped with the improved work-feeding mechanism.

Fig. 2 represents an enlarged transverse vertical section taken substantially along the line 2—2, Fig. 1.

Fig. 3 represents a horizontal section taken substantially along the line 3—3, Fig. 2, showing the orientation of the feed-bars and their feed-dogs.

Fig. 4 represents a longitudinal vertical section taken substantially along the line 4—4, Fig. 2.

Fig. 5 represents a transverse vertical section taken substantially along the line 5—5, Fig. 4.

Fig. 6 represents a vertical section taken substantially along the line 6—6, Fig. 4.

Fig. 7 represents a vertical section taken substantially along the line 7—7, Fig. 4.

The sewing machine illustrated in the accompanying drawings has the usual bed 10 in which is journaled a rotary bed-shaft 11 driven by a belt 12 from a main arm-shaft (not shown) located in the machine-arm. Operatively connected to the rotary bed-shaft 11 through the gear-box 13 is a loop-taker 14 in the form of a rotary hook complementary to a thread-carrying needle 15 carried in the lower end of a needle-bar 16 (Fig. 2) journaled for endwise reciprocation in the overhanging bracket-arm (not shown). The work to be stitched is depressed into contact with a throat-plate 17 by a presser-foot 18 carried on the lower end of a spring-pressed presser-bar 19 endwise slidable in the overhanging bracket-arm.

Opposing the presser-foot 18 in feeding the work are two feed-dogs 20 and 21. In the ma-

chine chosen to illustrate the present invention, the two feed-dogs are actuated in a manner such that the feed-dog 20 advances the work in one direction twice in succession, following which the feed-dog 21 returns the work once in the opposite direction, this sequence of feeding strokes being used particularly in the production of "fagoting" and "hem-stitching." The feed-dog 20 is secured, preferably by screws 22 (Fig. 3), to a feed-bar 23 pivotally connected at one end by pintles 24 to the upper ends of a pair of rock-arms 25 preferably integral with a feed-advance rock-shaft 26 supported on pintles 27 to extend longitudinally of the bed 10. The feed-advance rock-shaft 26 is actuated by means of a rock-lever 28 which is clamped on the reduced inner end of the rock-shaft 26 and connected by a pitman 29 to an adjustable eccentric 30 fast on the rotary bed-shaft 11. The eccentric 30 is of well known design and is constructed substantially in accordance with the disclosure in the U. S patent of W. Myers, No. 2,128,031, granted Aug. 23, 1938. Rotation of the bed-shaft 11 will impart an oscillatory movement 10 to the rock-shaft 26, thus causing the feed-dog 20 to undergo feed-advance and -return motions.

The feed-dog 21 (Fig. 3) is secured, preferably by screws 31, on a second feed-bar 32 pivotally connected at one end by a pin 33 to the upper end of a rock-lever 34 preferably integral with a second feed-advance rock-shaft 35 supported on pintles 36 to extend longitudinally of the bed 10 and in substantially parallel relation with the first feed-advance rock-shaft 26. At its inner end, the second feed-advance rock-shaft 35 has clamped on it a rock-lever 37 connected by a pitman 38 to a second adjustable eccentric 39 also fast on the rotary bed-shaft 11. It will be understood that rotation of the bed-shaft 11 will also oscillate the rock-shaft 35 and through the feed-bar 32 impart feed-advance and -return motions to the feed-dog 21. It will be appreciated that the direction of the feed-advance strokes of the feed-dog 20 are in a direction from right to left in Fig. 2, while the feed-advance strokes of the feed-dog 21 will be in the opposite direction. The opposite directions of the feed-advance strokes of the two feed-dogs 20 and 21 are obtained by setting 180 degrees apart the eccentricities of the two adjustable eccentrics 30 and 39. Thus, it will be obvious that during the advancing stroke of the feed-dog 20 in a direction away from the operator, the feed-dog 21 is undergoing an advancing stroke in the direction of the operator.

In order that each of the feed-dogs 20 and 21 will be effective in proper sequence, means are provided whereby each of the feed-dogs is periodically raised to a height in which its serrated surface is above the level of the top of the throat-plate 17. When this occurs the feed-dog grips the work in opposition to the presser-foot 18 and advances it an amount determined by the set eccentricity of the actuating eccentric. It will be observed in the drawings that the feed-bars 23 and 32 are forked as at 43 and 41 at their front ends to embrace slide-blocks 42 and 43 pivoted on the free ends of a pair of lift rock-arms 44 and 45 clamped on the ends of a pair of coaxially and telescopically disposed feed-lift rock-shafts 46 and 47. The outer feed-lift rock-shaft 46 is journaled on the inner feed-lift rock-shaft 47 which is supported by pintles 48 secured in the bed 10. Adjacent the standard-end of the machine, the coaxial feed-lift rock-shafts 46 and 47 have clamped thereon a pair of rock-levers 49 and 50. At their free ends each of these rock-levers carries a follower roller 51, 52 yielding held by the coil-springs 53, 54 in peripheral contact with suitable lift-cams 55, 56 mounted on a rotary countershaft 57 journaled in bearings 58 and 59 provided in the bed 10. The countershaft 57 is driven from the bed-shaft 11 through the reduction gears 60 and 61, the gear ratio being such that the countershaft rotates once for each three rotations of the bed-shaft 11. It will be observed from Fig. 7 that the cam 55 has two lobes and that the cam 56 has only one lobe, the two cams being so mounted on the countershaft 57 (Fig. 6) that the three cam-lobes are spaced from each other 120° circumferentially of the countershaft 57. Upon operation of the machine, the follower-rollers 51 or 52 ride on their respective cam-lobes and the rock-shafts 46 and 47 are caused to turn about the aligned axes of the two pintles 48 and, through the rock-arms 44 and 45, raise the feed-dogs 20 and 21 above the throat-plate 17 into effective work-feeding position. In the preferred embodiment of the invention, the speed ratio between the countershaft 57 and the rotary bed-shaft 11 is determined by the total number of feeding strokes of both feed-dogs in producing the desired stitch-pattern. In the machine illustrated in the drawings, the stitch-pattern comprises three feeding strokes, two forward and one backward, and therefore the speed ratio between the countershaft 57 and bed-shaft 11 is three-to-one. In the event the stitch pattern required a total of four stitches per pattern the speed ratio would then be correspondingly changed.

From the above description, it will be understood that during the operation of the machine, rotation of the bed-shaft 11 will, through the medium of the adjustable eccentrics 30 and 39, impart continuous feed-advance and -return movements to each of the feed-dogs 20 and 21. During this continued action of the feed-dogs 20 and 21 they are periodically elevated into effective position by the lift-cams 55 and 56 against the action of the coil-springs 53 and 54. Lift-cam 55 is formed with two lobes while lift-cam 56 is formed with only one lobe, and since these lobes are circumferentially spaced 120 degrees apart on the countershaft 57 which makes only one revolution for each three reciprocations of the needle, it follows that the feed-dog 20 is rendered effective for two successive stitches following which the feed-dog 21 is rendered effective

for only one stitch. Inasmuch as the adjustable eccentrics 30 and 39 are 180 degrees out of phase, the feed-dogs 20 and 21 are effective to feed the work in opposite directions. The setting of the present machine is such that the feed-dog 20 advances the work for two stitch-lengths in a direction away from the operator, while the feed-dog 21 returns the work a single stitch-length towards the operator. The amplitudes of the work-advancing movements imparted by the dogs 20 and 21 can be individually controlled by the separate adjustment of the eccentrics 30 and 39, and to facilitate this adjustment there are provided two spring-elevated detents 62 and 63 which can be manually depressed to lock the adjusting members of the eccentrics in the manner fully explained in the above mentioned Myers patent.

Having thus set forth the nature of the invention, what we claim herein is:

- 20 1. A work-feeding mechanism for sewing machines comprising a pair of feed-dogs, a pair of feed-advance and -return eccentrics, a first shaft carrying said eccentrics, operating connections between said feed-dogs and eccentrics, feed-lift mechanism including a cam for each of said feed-dogs, and a second shaft carrying said cams and operated at a speed different from that of said first shaft.
- 25 2. A work-feeding mechanism for sewing machines comprising a pair of feed-dogs, a pair of feed-advance and -return eccentrics, a first shaft carrying said eccentrics, operating connections between said feed-dogs and eccentrics, feed-lift mechanism including a cam for each of said feed-dogs, and a second shaft carrying said cams and operatively connected to said first shaft to rotate at a speed less than said first shaft.
- 30 3. A work-feeding mechanism for sewing machines comprising a pair of feed-dogs, a pair of feed-advance and -return eccentrics, a first shaft carrying said eccentrics, operating connections between said feed-dogs and eccentrics, feed-lift mechanism including a cam for each of said feed-dogs, a second shaft carrying said cams, and gearing operatively connecting said second shaft to said first shaft for rotating said second shaft at a lesser speed than said first shaft.
- 35 4. A work-feeding mechanism for sewing machines comprising a pair of feed-dogs, a pair of feed-advance and -return eccentrics, a first shaft carrying said eccentrics, operating connections between said feed-dogs and eccentrics, feed-lift mechanism including a cam for each of said feed-dogs, one of said cams having a plurality of feed-dog lifting lobes and the other of said cams having a lesser number of feed-dog lifting lobes, and a second shaft carrying said cams and operated at a speed less than that of said first shaft.
- 40 5. A work-feeding mechanism, for sewing machines comprising a pair of feed-dogs, an actuating shaft, a pair of feed-advance and -return eccentrics mounted on said shaft with their maximum eccentricities spaced apart circumferentially of said shaft, operating connections between said feed-dogs and eccentrics, and feed-lift mechanism operatively connected to said feed-dogs for elevating said feed-dogs into effective work-feeding position.
- 45 6. A work-feeding mechanism for sewing machines comprising a pair of feed-dogs, an actuating shaft, a pair of feed-advance and -return eccentrics mounted on said shaft with their maximum eccentricities spaced apart circumferentially of said shaft, operating connections be-

tween said feed-dogs and eccentrics, and feed-lift mechanism including a cam for each of said feed-dogs for elevating said feed-dogs into effective work-feeding position, said cams timed to successively render effective one of said feed-dogs a plurality of times following which the other feed-dog is rendered effective for a lesser number of times.

7. A work-feeding mechanism for sewing machines comprising a pair of feed-dogs, a rotary actuating shaft, a pair of feed-advance and -return eccentrics carried by said rotary actuating shaft, operative connections between said eccentrics and feed-dogs, a pair of feed-lift rock-shafts operatively connected to said feed-dogs, a countershaft driven at a speed different from that of said rotary actuating shaft, a pair of feed-lift cams mounted on said countershaft, and a rock-lever connected to each of said feed-lift rock-shafts and engaging its respective cam on said countershaft.

8. A work-feeding mechanism for sewing machines comprising a pair of feed-dogs, a pair of rotary feed-advance and -return eccentrics, feed-dog operating devices connected to said eccentrics, a pair of coaxially arranged feed-lift rock-shafts operatively connected to said feed-dogs, a countershaft connected to be driven at a speed different from that of said rotary eccentrics, a pair of feed-lift cams mounted on said countershaft, and a rock-lever secured to each of said feed-lift rock-shafts and engaging its respective cam on said countershaft.

9. A work-feeding mechanism for sewing machines comprising a pair of feed-dogs, a pair of rotary feed-advance and -return eccentrics, feed-dog operating devices including a pair of substantially parallel feed-advance rock-shafts connected to said eccentrics, a pair of coaxially arranged feed-lift rock-shafts operatively connected to said feed-dogs, a countershaft connected to be driven at a speed different from that of said rotary eccentrics, a pair of feed-lift cams mounted on said countershaft, and a rock-lever secured to each of said rock-shafts and 45

engaging its respective cam on said countershaft.

10. A work-feeding mechanism for sewing machines comprising a pair of feed-dogs, a rotary actuating shaft, a pair of feed-advance and -return eccentrics mounted on said shaft with their maximum eccentricities spaced apart circumferentially of said shafts, feed-dog operating devices including a pair of feed-advance rock-shafts connected to said eccentrics, a pair of coaxially arranged feed-lift rock-shafts operatively connected to said feed-dogs, a countershaft geared to said rotary actuating shaft to be driven at a speed different from that of said actuating shaft, a pair of feed-lift cams mounted on said countershaft, and a rock-lever secured to each of said rock-shafts and engaging its respective cam on said countershaft.

11. A work-feeding mechanism for sewing machines comprising a pair of feed-dogs having oppositely directed effective work-advancing movements, an actuating shaft, a pair of feed-advance and -return eccentrics mounted on said shaft with their maximum eccentricities spaced apart circumferentially of said shaft, feed-dog operating devices connected to said eccentrics, and feed-lift mechanism operatively connected to said feed-dogs and timed in its effective action for sequentially rendering said feed-dogs effective in feeding the work in opposite directions.

12. Work-feeding mechanism for sewing machines, including a work-support, comprising, a pair of feed-dogs having oppositely directed effective work-advancing movements through said work-support, operative mechanism for imparting feed-advance and return movements to said feed-dogs, and feed-lift actuating mechanism including a plurality of cams operatively connected to said feed-dogs and timed to effect work-advancing movements of one of said feed-dogs during ineffective return movements of the other of said feed-dogs.

ARTHUR N. HALE.
RUSSELL CARMICHAEL.
